(57) **CLAIM**

I claim the ornamented design for a tool case, as shown in the drawings.

DESCRIPTION

FIG. 1 is a perspective view of a tool case showing my new design;

FIG. 2 is a front elevational view thereof;

FIG. 3 is a top plan view thereof;

FIG. 4 is a right side elevational view thereof, showing the latch side;

FIG. 5 is a bottom plan view thereof;

FIG. 6 is a left side elevational view, showing the hinge side;

FIG. 7 is a rear elevational view thereof;

FIG. 8 is a perspective view of a modified embodiment of the tool case;

FIG. 9 is a front elevational view thereof;

FIG. 10 is a top plan view thereof;

FIG. 11 is a right side elevational view thereof, showing the latch side;

FIG. 12 is a bottom plan view thereof;

FIG. 13 is a left side elevational view thereof, showing the hinge side; and,

FIG. 14 is a rear elevational view thereof.
